United States Patent Office

Des. 180,874
Patented Aug. 27, 1957

180,874

AUTOMOBILE

Paul W. Gillan, Detroit, Mich., assignor to General
Motors Corporation, Detroit, Mich., a corporation of Delaware

Application October 31, 1956, Serial No. 43,611

Term of patent 7 years

(Cl. D14—3)

The dominant features of my design are shown in the full line portions of the drawings.

I claim:

The ornamental design for an automobile, substantially as shown and described.
